UNITED STATES PATENT OFFICE.

THOMAS WELCH, OF PAW PAW, MICHIGAN.

CAR-COUPING.

SPECIFICATION forming part of Letters Patent No. 373,210, dated November 15, 1887.

Application filed March 23, 1887. Serial No. 232,804. (No model.)

To all whom it may concern:

Be it known that I, THOMAS WELCH, a citizen of the United States, residing at Paw Paw, county of Van Buren, State of Michigan, have 5 invented a new and useful Car-Coupling, of which the following is a specification.

This invention has for its object certain improvements in the means for coupling cars, substantially as below described and claimed.

10 In the drawings forming a part of this specification Figure 1 is a side elevation showing the contiguous ends of two broken cars with couplings attached; Fig. 2, a plan of lettered details; Fig. 3, a section on the dotted line 1 1 15 in Fig. 1, looking from a point at the left hand; and Fig. 4 is an under view of lettered details in Fig. 1.

Referring to the lettered parts of the drawings, A are the cars having the ordinary draw-bars, B. The under side of the draw-bar, at right hand in Fig. 1, is provided with a hook open at the rear. This hook X may be made integral with the draw-bar; but for draw-bars already in use the hook is made integral with 25 a bar, U, attached to the under side of the draw-bar by means of confining-clips V, or by any other suitable means.

At C is a spring-actuated bridge, the rear end of said bridge being passed through a loop 30 (pendent from the under side of the car) and resting on a spring, i. This loop E has one side removed in Fig. 1, showing the spring supported by the lower bar of said loop. The forward end of the bridge C is hinged to the lower 35 arched bar of the loop d, Fig. 3. The bridge C is thus directly beneath the hook X, and in its normal position is held in contact with said hook. From the hook to the forward end the bridge inclines downward. One end of the 40 link D is attached in a hinged manner by means of the bar U', having the loop or eye which retains the loop end of the link. This bar is attached to its draw-bar B by like clips, V. If preferred, the construction may be 45 alike at each end of both cars, as shown beneath the right-hand car. The link is supported, when the cars are not coupled, by a loop, e, in substantially a horizontal position, or nearly so. The link D is bowed downward 50 between its two ends, Fig. 1, so as to clear the bumpers; but the ordinary straight link made

of sufficient length may be used. The link D is made heavier in the center than at the ends to obviate danger of straightening.

In the operation of coupling, the cars are 55 brought together end to end, as in Fig. 1, which action causes the end of the link to slide up the incline of the bridge C, and as the cars are brought closer together the bridge is forced to tilt downward against a spring resistance 60 by the end of the link which is forced behind the hook X. (In Fig. 1 the end of the link is just ready to force the bridge down.) When the cars start ahead, the end of the link catches the hook, as in Fig. 4, because the spring i 65 has raised the bridge against the hook X, which keeps the link up to enter the hook. Such a coupling will work successfully on cars of different heights.

At S is a lever reaching to the top of the car, 70 and fulcrumed to the bracket t at the lower end. It is retained in place by loops on the side of the car. The lever has an extension, r, adapted to bear upon the bridge C and force it down when the lever is swung forward. 75 The dotted lever and bridge in Fig. 1 show this action, which is had when uncoupling the cars to allow the link to lower below the hook X, so as to be drawn out of the coupling.

Of course, in uncoupling, the cars are slackened enough to carry the end bar of the link back of the end of the hook. The handles y b of the lever S are connected by a rod, v, pivoted to them. The lower handle, which has a shoulder to catch over a lug on the loop e, may 80 be used to operate the lever from the ground, and the handle y to raise the latch-handle b to unlatch it. n shows a rod which may be attached to the lever S for the engineer's use.

Having thus described my invention, what 90 I claim is—

1. In a car-coupling, a draw-bar having a hook on the under side, in combination with a bridge adapted to contact said hook, inclined downward therefrom, pivotally supported at 95 one end, and spring-supported at the other end, a link bowed downward between the ends, and a suitable lever for bearing the bridge down to allow the link to uncouple, substantially as set forth.

2. In a car-coupling, the combination of a draw-bar, a bar (bearing a hook) attached to

the under side by confining - clips, a bridge adapted to contact said hook, the bridge being inclined at one end downward, pivotally supported at said end and spring-supported at the other end, a coupling-link, and a suitable lever for bearing the bridge down when uncoupling, substantially as set forth.

In testimony of the foregoing I have hereunto subscribed my name in presence of two witnesses.

THOS. WELCH.
